UNITED STATES PATENT OFFICE.

ELMER J. KREIDLER, OF HECKTOWN, PENNSYLVANIA.

MATCH.

1,002,526.

Specification of Letters Patent. Patented Sept. 5, 1911.

Application filed June 1, 1911. Serial No. 630,593.

To all whom it may concern:

Be it known that I, ELMER J. KREIDLER, a citizen of the United States, residing at Hecktown, in the county of Northampton 5 and State of Pennsylvania, have invented certain new and useful Improvements in Matches, of which the following is a specification.

My invention relates to improvements in 10 matches, the object of the invention being to provide a match comprising a single stem having heads at both ends, and an intermediate section of non-combustible material with the stem weakened at the ends 15 of said non-combustible section.

With this and other objects in view, the invention consists in certain novel features of construction, and combinations and arrangements of parts, as will be more fully 20 hereinafter described and pointed out in the claim.

The accompanying drawing is a view in elevation illustrating my improvement.

1, represents a match stem or stick, which 25 is provided on both ends with combustible heads 2. The intermediate portion 3 of the stick is rendered non-combustible in any suitable manner, and at the ends of the non-combustible portion, the stem or stick

is weakened by means of annular grooves 30 4. The purpose of this construction is to permit one end of the match to be used, and then broken off, leaving the other end for future use. The non-combustible section prevents the match from burning beyond a 35 certain point, and also prevents any burning of the fingers.

The invention is not limited to any particular method of rendering the intermediate portion of the match non-combustible. 40 I may employ saline substances for the purpose, as for example, borax, alum, phosphate of soda, or ammonia.

Having thus described my invention, what I claim as new and desire to secure by 45 Letters Patent is:

A match comprising a stick having heads at both ends and having an intermediate non-combustible section, and said stick weakened at both ends of the non-combustible section, substantially as described. 50

In testimony whereof I have signed my name to this specification in the presence of two subscribing witnesses.

ELMER J. KREIDLER.
